UNITED STATES PATENT OFFICE.

WILLIAM H. BARNETT, OF KNOXVILLE, TENNESSEE.

SEWING MACHINE.

Application filed January 3, 1921. Serial No. 434,537.

To all whom it may concern:

Be it known that I, WILLIAM H. BARNETT, a citizen of the United States, and a resident of Knoxville, Tennessee, have invented new and useful Improvements in Sewing Machines, which invention is fully set forth in the following specification.

The object of this invention is the provision of a sewing or embroidering machine and particularly a machine for producing a class of embroidery known as Egyptian embroidery, Oriental embroidery, carpet embroidery, or Persian woven fabric, such embroidery being now extensively used, for example, on dresses and ladies' wearing apparel generally, table covers, scarfs, sofa pillows and other interior decorations. Heretofore this class of embroidery has been commonly produced by hand only, so far as I am informed; but whether performed by hand or by my machine, the stitches are first produced in loop formation, that is to say, thread or yarn is carried through the cloth or fabric in a succession of loops which are left projecting from the fabric at the right side of the finished work, succeeding lines of stitches being closely grouped or positioned so as to produce a close matting of the loops conforming to the desired pattern or design of embroidery. The length of projection of these loops at the right side of the work may vary as desired, but usually in such embroidery they are made relatively long, anywhere from three-eighths of an inch up. The projecting thread loops are then trimmed just enough to clip the loops leaving two projecting threads for each loop. The embroidery may be made all in one color of thread or yarn, or in combinations of colors. Improvement upon the machine of my pending application Sr. No. 410,039 filed Sept. 13, 1920, is a further object.

The aforesaid and other objects are attained by the present invention. What is now believed to be the preferred embodiment thereof is illustrated in the accompanying drawings, wherein—

- Fig. 1 is a perspective view of the complete machine;
50 Fig. 2 is a rear elevation thereof;
Figs. 3 and 4 are detail views of the feed-dogs;
Fig. 5 is a horizontal sectional view on line 5—5 of Fig. 2;
55 Fig. 6 is a vertical section on line 6—6 of Fig. 5;

Figs. 7 and 8 are detail views of parts;

Fig. 9 is a perspective view looking toward the head of the machine with the detachable section or cover of the head removed;

Fig. 10 is an elevation (on line 10—10 of Fig. 2) looking into said cover and showing parts of the mechanism associated therewith;

Figs. 11 and 12 are elevations looking toward the end of the head of the machine with the cover omitted excepting a portion of the lower edge thereof, and with operating parts shown in different positions in the two views respectively,

Figs. 13, 14 and 15 are detail views, Fig. 13 being in section on line 13—13 of Fig. 11;

Fig. 16 is an elevation (with some parts in section) of the thread control mechanism looking in the direction of the arrows on line 16—16 of Fig. 2;

Fig. 17 is a horizontal section on line 17—17 of Fig. 16;

Fig. 18 is a vertical section on line 18—18 of Fig. 17;

Fig. 19 is a vertical section on line 19—19 of Fig. 16;

Fig. 20 is a vertical section through the throat plate and its adjusting mechanism;

Fig. 21 is a horizontal section on line 21—21 of Fig. 20;

Fig. 22 is a plan view of the throat plate; and

Fig. 23 is a detail perspective of the presser-foot.

Machine frame and main driving connections.—Referring to the drawings, 30 is an ordinary sewing machine table. The machine frame comprises a hollow upright column or standard 31, hollow horizontal arm or goose-neck 32, and a hollow upright head 33 preferably integrally formed or cast in one piece, the flanged base of the standard resting upon and fixed to the table. A detachable hollow head section or cover 34 is secured in position to the head by four screws 35. The main drive shaft 36 is supported horizontally in the hollow arm 32 in bearings 37 (Fig. 5) and 38 (Fig. 2) and is suitably driven through a belt 39 engaging pulley 40 on one end of the shaft.

Needle-bar and driving connection therefor.—One or more tubular needles 41, best shown in Fig. 10, are preferably used. While only one needle is shown in the drawings, one or a plurality of needles may be

used according to whether a single or two or more parallel lines of stitches are to be formed. The needle-bar 42, preferably of rectangular cross-section, is simultaneously 5 reciprocated longitudinally up and down to cause the needle to pierce and then withdraw from the work and swung laterally back and forth at its lower end to reciprocate or oscillate the needle sidewise a distance equal to the length of stitch being 10 formed. As shown (see Figs. 5 and 10) needle-bar 42 has therethrough three longitudinal thread-passages 43 each slightly enlarged at its lower end to receive a needle 15 41 clamped in place by a set-screw 44 with the thread passages of the bar and needle in axial alinement. While only one needle is shown, three needles may be used in the machine illustrated, and a needle-bar having 20 more thread passages may be provided where it is desired to use more than three needles. Needle-bar 42 moves in slots or notches 45 and 46 in the top and bottom flanges of cover 34 and is guided and controlled in its movement by means presently 25 described.

The means for longitudinally reciprocating the needle-bar are as follows: An elongated wheel or hub 47 is secured by set-screws to the inner end of drive-shaft 36, as best shown in Figs. 5 and 6. An elongated worm-gear 48, Fig. 8, has an axial stem or shaft 49 fixed thereto and projecting therefrom at both ends with a screwing 30 head 50 at one extremity of the shaft. Said worm-gear is positioned in a transverse chamber or recess 51, Figs. 5 and 6, in the wheel 47. Two collar plates 52 and 53, Figs. 5, 6 and 7, are removably secured in a groove 35 across the periphery of wheel 47 by two screws 54, 55, notches in the edge of each plate (Fig. 7) embracing the shank of each screw beneath the head thereof. Two other semi-circular notches 56 in said plates 40 embrace the shaft 49 of the worm-gear adjacent its head 50 and constitute a supporting bearing. At its other end said shaft 49 is supported in a bearing opening in the wall 45 of wheel 47 at the bottom of chamber 51, as shown in dotted lines, Fig. 5. Thus, the worm-gear 48, supported at its opposite ends by said bearings, may be rotated by a screw-driver projected into engagement with screw head 50 through an opening 57 in the front 50 wall of the head 33 of the machine frame. 55 58 is an adjustable plate bearing against the flat outer end surface of wheel 47 and having thereon a rib 59 slidable in an undercut channel 63 in said surface, said channel at 60 its bottom opening into the chamber 51. Worm-teeth on the inner edge of rib 59 engage the worm-wheel 49, whereby rotation of the latter imparts longitudinal adjustment to the plate 58. By such adjustment 65 the crank-wrist or pivot stud 60 fixed to

plate 58, will be moved nearer to or further from the axis of wheel 47 about which it rotates. At its upper end a pitman 61 engages crank-wrist 60 and at its lower end engages pivot stud 62 fixed to needle-bar 42, thereby longitudinally reciprocating the latter, the amplitude of such movement depending upon the position of eccentricity to which crank-wrist 60 is adjusted and determining the length of loop of thread or 70 yarn projected through the fabric by the needle at each reciprocation thereof, which length as before stated is usually from three-eighths of an inch up.

Feed-mechanism.—A top-feed is used. 80 There are two parallel feed-dogs 65, 66, Figs. 3, 4, 9 and 10, with teeth on their bottom surfaces. They are moved or swung opposite the direction of feed while lifted from the work or fabric, then lowered to yieldingly engage the work, and then moved or swung backward while gripping the work to feed or advance the same the length of one stitch for each such movement. The feed-dogs are spaced apart and each has two right-angled arms 67, 68, at its ends respectively, the corresponding arms on the two dogs projecting toward each other, and providing rectangular space between the feed-dogs slightly wider and considerably longer than the presser-foot which operates in said space, such length allowing for the forward and backward movement of the feed-dogs with relation to the presser-foot. There is a clearance between the ends of the arms 67, 68, at the medial dotted line of Fig. 9. Two upstanding longitudinal flanges on each feed-dog form a groove to receive a foot 69 on a vertical stem 70. A screw pivot pin 71' pivots each feed-dog to its foot at a point toward the forward ends of both foot and dog, the bottom edge of the foot being inclined upward in opposite directions from a point beneath the pivot, as best shown in Fig. 4, whereby each feed-dog has a pivotal rocking motion with a normal tendency to tilt downward at its rear end because of the positioning of the pivot nearer the front end. When an extraordinary thickness of fabric, 95 such as part of an embroidery design or a heavy seam, is engaged under the forward end of one of the dogs with a lesser thickness of work under its rear end, the dog tilts upward at its forward end so as to engage work throughout approximately its entire length, such tilting being reversed with like effect when the greater thickness is under the rear end of the dog. The two stems 70, 70 have vertical movement in two sockets 71, 71 (Figs. 9 and 10) in opposite ends respectively of a block or plate 72. A transverse stop pin 73 through each stem 71 works in a slot 74 of block 72, prevents turning of the stem in its socket and thereby holds each dog 100 in its proper alinement with the two dogs 105 110 115 120 125 130

parallel to each other. A coiled expansion spring 75 in the upper closed end of each socket 71 bears against the upper end of stem 70 in the socket to yieldingly press the corresponding feed-dog into engagement with the fabric on the throat-plate. As the pressure of each feed-dog is thus exerted by its spring 75 the two dogs may independently adjust themselves to any different thicknesses of fabric or work thereunder, for instance, the left-hand dog may be engaging a thickness of one quarter of an inch while that part of the work under the right hand dog may be of much less thickness with both dogs uniformly gripping the surface of the work or fabric to feed or advance it in the feed stroke of the dogs. This independent movement of the two dogs and the aforesaid tilting of each dog insures uniform feed action regardless of differences and variations of thickness of the work or fabric engaged by the dogs.

A feed bar 77 has a longitudinal bore or elongated socket in its lower end to receive stem 76 rising centrally from the block 72 and adjustable to different elevations in the socket, a pin 78 through the stem being movable in slots 79 at opposite sides of bar 77 to prevent turning of the stem in its socket. Two set-screws 80 at opposite sides of the lower end of bar 77 engage stem 76 to secure or set it and the feed members supported therefrom at the desired elevation dependent upon the length of needle-bar stroke which in turn determines the length of loop to be projected through the work at each stroke of the needle. In other words, for an adjustment of the needle-bar actuating means to lengthen the stroke of the needle, the stem 76 is set at a correspondingly higher position in its socket, and vice versa. Feed bar 77 is preferably rectangular in cross-section and throughout its length slidably bears against one side of the needle-bar 42 and with the latter projects through the notches 45 and 46 in the top and bottom walls of cap 34 of the head of the frame. Antifriction rollers 80 and 81 at opposite ends of slot 45, Fig. 10, bear against bars 42, and 77 respectively, and form a kind of fulcrum for the swinging of said bars as they are also reciprocated longitudinally. Feed-bar 77 is reciprocated from needle-bar 42 by a bell-crank lever 82 pivoted to bar 77 by a screw-stud 87 and having a long arm 83 formed with a slot embracing a roller stud 85 on bar 42, and a short arm 84 slotted or forked to embrace a roller stud 86 fixed to the cap 34. Upon reciprocation of the needle-bar 42 downward from its position in Fig. 10, its roller stud 85 travels downward in the slot of arm 83, swings said arm toward the right (Fig. 10), and by the action of arm 84 against fixed stud 86 reciprocates bar 77 downward through its pivotal connection 87

to the bell-crank lever. The amplitude of reciprocation of the feed-bar 77 is thus considerably less than that of the needle-bar 42 because the needle must travel further in penetrating the work and then rising clear of it than is required in engaging the feed-dogs with and disengaging them from the work.

The means for imparting forward and backward movement to the feed-dogs, and at the same time to the needle, are as follows: A heavy blade spring 90 (Fig. 10) is secured at its upper end by screws to a boss 91 on the interior of cap 34 and at its lower slightly curved end bears against the rear face of feed-bar 77 and thus tends to swing said bar and with it needle-bar 42 to the limit (determined by a stop presently described) of their forward movement, the bars in so swinging pivoting at their upper ends between the rollers 80 and 81. Rearward swing or feed-movement is imparted to the bars through a bell-crank lever 95 having a hub 92 (Fig. 12) embracing a fulcrum stud 93 on the wall of the head of the machine. A depending long arm of lever 95 has a right angle extension (Fig. 6) carrying a roller 94 bearing against the flat side of needle-bar 42. A bent lever 96, Figs. 5, 6, 12 and 13, fulcrumed against a roller 97 is pivoted at one end to a short arm of bell-crank lever 95 and at its other end carries a roller 98 bearing against a cam surface 99 of wheel 47. A blade spring 100, secured to lever 96 and at its free end engaging under hub 92 of lever 95, exerts its tension to always maintain lever 96 up in position for its roller 98 to bear against the cam surface 99. Rotation of said cam surface acts to move the upper end of lever 96 outward thereby rocking said lever on its fulcrum roller 97 and actuating bell-crank lever 95 to swing the lower end thereof rearward towards the right in Fig. 10, or left in Figs. 11 and 12. Such swinging of lever 95 with its roller 94 bearing against the needle-bar 42, swings both that bar and presser-bar 77 rearward in their feed stroke against the yielding resistance of spring 90 and with the feed-dogs and needle in engagement with the work. The amplitude of such backward movement is dependent upon the position of fulcrum roller 97 with relation to the lever 96 and may be increased by shifting said fulcrum roller 97 toward the upper end of said lever, or decreased by a shift in the other direction. For the accomplishment of such shifting or adjustment, roller 97 is mounted at one end of a bell-crank lever 101 fulcrumed on a stud 102 threaded into the wall of machine head 33, Figs. 11 and 12. A stem 103 threaded into the other end of lever 101 (Fig. 13) projects through a curved slot 104 of the wall of the head and then through a similar slot in a gauge-plate 130

105 secured to the exterior of said wall by screws, Fig. 14. A block or collar 106 is keyed on to the stem 103 and has teeth engaging transverse teeth or serrations of gauge-plate 105 to prevent slipping when the parts are set to a certain position of adjustment. A coiled spring 107 on stem 103 is enclosed by a sleeve 108 also on said stem, with a nut 110 threaded on to the outer extremity of said stem and retaining all the parts in position thereon with the spring 107 bearing at one end against the top wall of its chamber in sleeve 108 and at its other end against collar 106. Turning the nut 110 down tight, as shown in Fig. 13, compresses spring 107 until the sleeve 108 contacts collar 106 and thereby locks its teeth in engagement with teeth of plate 105, thus securing bell-crank lever 101 and its fulcrum roller 97 against movement. To adjust the position of these parts the nut 110 is loosened, the sleeve 108 is moved out of engagement with collar 106 by expansion of spring 107, and the stem (carrying with it lever 101) may be moved to a new position of adjustment in slot 104 the teeth on collar 106 riding over teeth on plate 105 under the yielding pressure of spring 107 against said collar. When the desired adjustment is attained the nut 110 is again tightened and the parts locked as in Fig. 13. When the low part of cam surface 99 comes under roller 98, as in Fig. 11, the spring 90 acts to swing the needle and feed-dogs (then elevated out of engagement with the work) and their bars forward a distance equal to the length of one stitch, until such movement is arrested by bell-crank lever 95 coming in contact with the felt tip of an adjustable stop-screw 111 threaded through the wall of head 33 and locked in the desired position of adjustment by a nut 112. Thus, the adjustment of stop-screw 111 on the one hand, and of bell-crank lever 101 with its fulcrum roller 97 on the other hand, determine the limits of forward and backward movement of the feed-dogs and needle and thereby the length of stitch formed, so that the length of stitch may be varied as desired by adjustment of said parts.

Presser-foot and operating mechanism therefor.—During the feeding of the work on the feed stroke of the feed-dogs, there is little, if any, pressure exerted upon the work by the presser-foot, and thus no resistance or interference therefrom to the advance of the work. But as soon as the feed movement is completed the presser-foot begins to yieldingly press upon the work, such pressure reaching its maximum as the needle pierces the work to thereby resist any tendency of the needle to press the work into the opening of the throat plate and below the upper work supporting surface of said plate. The presser foot 115, best shown in

Figs. 1 and 23, is of rectangular outline to occupy the rectangular space (Fig. 3) between the feed-dogs 65 and 66, but somewhat shorter than said space to allow for the backward and forward movement of the feed-dogs with relation to the presser-foot which latter has only up and down movement. The foot is slightly upturned at its forward edge and has therethrough an approximately rectangular opening 116 of a width to accommodate a plurality of needles arranged side by side and of a length sufficient to accommodate the backward and forward swinging of such needles in the feed and return movements thereof with the feed-dogs as already explained. The shank or hub 117 of the presser-foot is longitudinally bored to receive the lower end of the bar 118 to which the presser-foot is clamped by a set-screw 119. Bar 118 extends upward through a bearing opening 120 in the bottom wall of the cap 34 and at its upper end enters a telescoping tubular bar 121 which is vertically movable in a bearing opening in the hereinbefore mentioned boss 91 and a bearing opening 122 of another inwardly projecting boss 123 at the top of the cover 34. A cap 124 screw-threaded into the upper end of bearing opening 122 has a central perforation therethrough into which the spout of an oil can may be inserted to inject lubricant for lubricating the contacting surfaces of the tubular member and its upper bearing opening, some of the lubricant also finding its way down the outside of the sleeve to lubricate the bearing thereof in the boss 91. A perforation 125 through the upper end wall of the tubular bar 121 admits some of the lubricant to the interior thereof and thus lubricates the contacting surfaces of the two bars 121 and 118 in the longitudinal sliding or telescoping movement thereof with relation to each other. A pin 126 through the bar 118 working in slots at opposite sides of the tubular bar 121 prevents relative turning of the bars which might throw the presser-foot out of proper alinement. A coiled expansion spring 127 housed in the upper end of tubular bar 121 bears at its upper end against the top wall of said bar and its lower end against the upper end surface of the bar 118, tending constantly to move the bar 118 outward or downward in the tubular bar 121 to the limit of movement permitted by contact of the stop pin 126 with the ends of its slots in bar 121. A hub or sleeve at the inner end of an arm 128 surrounds tubular bar 121 and is fixed thereto by two set-screws (Fig. 10), said arm 128 projecting through a slot in the rear of the cap 34. An elongated upright slot at the outer end of arm 128 has therein an antifriction roller 129 journaled on a pin bridging the slot. A rock-lever 130, Figs. 5, 9 and 10,

has a forked end reaching into the aforesaid slot and embracing roller 129. A screw stud 131 (Figs 5 and 9) has thereon an antifriction roller 132 in a slot 133 of lever 130 thus constituting a fulcrum on which said lever may simultaneously rock and reciprocate longitudinally. The screw stud 131 is threaded at its inner end into a plate 134 which is fastened by screws (Fig. 9) to the rear wall of the head 33 over an opening through said wall. An angle lever 135 is pivoted at one end by a stud 136 (Figs. 2 and 9) to the rear face of the head of the machine and at its other end is pivotally connected to one end of rock-lever 130. A stud 137 projecting inwardly from lever 135 through a slot 138 in the rear wall of the machine head has at its inner end a roller 139 (Fig. 5) engaging a cam groove 140 formed continuously about the surface of the wheel 47. In the rotation of the wheel said cam groove acts through the roller 139 and stud 137 to swing the lever 135 back and forth on its pivot 136, thereby imparting simultaneous rocking and reciprocating movement to the lever 130 on its fulcrum, the forked end of lever 130 thus moving up and down and imparting vertical reciprocating movement to the tubular bar section 121 of the presser-bar through the arm 128 fixed to said tubular bar. Downward movement of the tubular bar compresses the spring 127 (Fig. 10) against the upper end of the bar 118 and thus increases the pressure which the spring exerts upon the presser-foot, this action being so timed that the tubular bar is at the limit of its downward movement and the spring exerting its maximum pressure when the needle is in the act of piercing the work, thus preventing the needle from forcing the work downward into the opening provided in the throat plate to receive the point of the needles and to accommodate the backward movement thereof while projecting through the work. When the needle reaches the limit of its downward stroke through the work the cam groove 140 and the connections operated therefrom are timed to begin upward movement of the tubular bar 121 to gradually relax the pressure exerted by the spring 127 upon the presser-foot and hence by the foot upon the work until a minimum of pressure, or practically no pressure, is reached when the feed of the work begins, at which time the pin 126 will contact the bottom of its slots (Fig. 10) and slightly lift the presser-foot out of engagement with the work. A coiled spring 141 connected between an arm 142 at the back of the top of the cover 34 and a lug on the arm 128 is extended by the downward movement of said arm actuated from the cam groove 140 and operating connections heretofore described. On the upward or re-

verse movement said spring 141 imparts a lift through the arm 128 and thereby assists the action of the cam groove and its connections.

The usual cam lever 143 pivoted in a slot 70 in the rear wall of cover 34 cooperates with a lug of a collar 144 secured by a set-screw to the bar 118 to lift said bar and with it the presser-foot to elevate the latter from the work when it is desired to shift the work 75 to bring the design thereof in proper relationship to the needle or for other reason. Such lifting of the foot when the tubular bar 121 is at the limit of its upward movement, as shown in Fig. 10, elevates the pin 80 126 from the bottom of its slots as also shown in said figure. Since work is shifted only when the feed-dogs and the needle are at the limit of their upward movement and thus clear of the work (at which time the bar 121 is also up as shown in Fig. 10), it is unnecessary to provide any means for elevating said dogs and needle when the presser-foot is lifted by the cam lever 143 as shown in Figs. 2 and 10. In this machine 85 90 when it is desired to entirely remove work from under the presser foot, feed-members, and needle, the work plate 145 about to be described should be lowered to afford ample clearance for withdrawal of the work and 95 for introduction of new work.

Work-support or throat-plate and adjusting means therefor.—145 is the work-plate or throat-plate having through its center a rectangular opening 146 beveled at its forward edge and of the same size as the opening 116 through the presser-foot, its width being sufficient to accommodate the maximum number of needles the particular machine is capable of using, and its length sufficient to accommodate the maximum forward and backward sidewise feeding movement of the needle or needles. Throat-plate 145 has a concentrically depending flange or hub 147 fitting in the upper end of a vertically movable tubular member 148 and secured in the desired position therein by two oppositely positioned set-screws 149 only one of which is shown in the drawings in Fig. 20. The member 148 is movable vertically 100 105 in the surrounding fixed tubular member 150 which at its upper end is secured in an opening of a plate 151 the latter being in turn secured by screws to the upper surface of the table 30 around an opening 156 thereof in and through which opening some of the parts now being described are positioned and project. A bottom plate 152 is screw-threaded onto the lower end of tubular member 150. Four bolts 153 threaded through 110 115 equidistant holes around the edge of plate 152 are adapted to be turned through said openings until the upper ends thereof bear against the bottom surface of the table 30 whereby the parts may be applied to tables 120 125 130

of different thickness. A wood screw 154 through a central bore of each bolt 153 is longer than the bolt and enters the wood of the table and makes impossible lateral shifting of the connection to the underside of the table. 155 is a worm-gear positioned in one side of the opening 156 through the table, said gear having an axle or shaft 157 journaled at its upper end in a socket 10 in the under side of plate 151 and at its lower end in an opening through the plate 152, a crank handle 158 at the lower extremity of said shaft serving to rotate it and the gear thereon. A collar 159 fixed 15 by a set-screw on shaft 157 and bearing upon the top of plate 152 serves to hold the worm-gear and shaft up in proper position. A rack-bar 160 is secured by screws to the outer surface of the vertically adjustable 20 tubular member 148, with the gear-teeth of the rack in engagement with the worm-gear, a slot 161 being formed in the tubular member 150 to accommodate the rack. As thus appears, the throat-plate 145 may be 25 raised or lowered to any desired position by rotation of the crank handle 158 and is thereby given the required adjustment to conform to the particular work being performed and length of loop which it is desired 30 to project through the fabric by the needle or needles.

Automatic thread supply and control mechanism.—The stitch formation which this machine is designed to produce requires 35 a free feeding or supplying of the thread to the needles on each down stroke thereof with practically no tension on the thread. To satisfy those conditions I provide means whereby, during each ascending movement 40 of the needle or needles when they are not consuming thread or exerting pull thereon, thread is pulled from the source of supply to provide an amount of slack thread sufficient for consumption of the needle in its 45 next downward loop forming stroke. In the operation of such means the thread is gripped at a point between the needles and the source of supply, and while so gripped a pull-off device acts upon the thread between 50 the point at which it is gripped and the source of supply to pull further thread from such source and provide slack therein which is then made available to the needles on their down stroke by releasing the 55 aforesaid grip upon the thread.

A plate 165 is applied to the top of the machine frame or casing at the right hand end thereof over an opening 166 (Figs. 16 and 19) through the casing wall. Two 60 standards 167 and 168 rise from an angular base bar 169 which bears upon the plate 165 and borders two edges thereof. Screws 170, of which three are shown in Fig. 16, pass through the base bar 169, plate 165 and 65 into the wall of the machine casing to secure

the parts in place. A block 171 secured to the upper end of standard 167 (Fig. 2) has therethrough three thread-eyes or passages 172; and a similar block 173 secured to the upper end of standard 168 (Fig. 16) has 70 therethrough three thread-eyes or passages 174 in approximate alinement with the aforesaid thread eyes 172 respectively. An up-standing long stroke lever 175 swings in the space between the standards 167 and 75 168 and has therethrough three thread-eyes 176. 177 (Fig. 2) is a standard mounted on the table 30 and supporting a shelf 178, and at its upper end having three over-hanging thread guides 179. Three thread 80 receptacles 180 are shown upon the shelf 178 in Figs. 1 and 2, each receptacle having a cover. Thread in ball or other suitable form placed in the three receptacles is led through a thread-eye centrally positioned in 85 each of the receptacle covers, the three threads thence passing in turn through the thread guides 179, thread-eyes 172 of block 171, thread-eyes 176 of lever 175, thread-eyes 174 of block 173, through eyes in an 90 upright thread guide 181 at the middle of the neck 32 of the machine, through thread-eyes positioned above the needle-bar in a thread guide 182 rising at an incline from the neck of the machine, thence downward 95 through the three longitudinal thread passages of the needle-bar 42 to the three needles when three needles are in use. Fig. 1 shows the use of only one thread as only 100 one needle appears in that view as well as other figures of the drawings such as Figs. 9 and 10. But in Fig. 2 the use of three threads is shown, but without any attempt to illustrate three needles in that or any other view of the drawing.

The means for actuating the lever 175 to pull thread from the source of supply, and also for gripping the thread during that operation, are as follows: The long stroke lever 175 and a short stroke lever 183 are 110 fulcrumed side by side upon a short horizontal shaft 184 between two collars 185, 185 fixed on said shaft by set-screws. Shaft 184 is supported at opposite ends in openings in lugs 186, 186 on the bottom of plate 165 and set-screws through said lugs clamp the ends of the shaft in the lugs. Lever 175 is forked at its lower end to embrace an eccentric 187 of considerable throw or stroke, and lever 183 is similarly forked to embrace an eccentric 188 of short stroke or throw, both said eccentrics being secured to the main drive-shaft 36 of the machine. From the eccentrics the two levers extend upward through the opening 166 in the top wall of the machine and through an opening 189 in plate 165. At its upper end lever 183 bears 120 against roller 190 journaled in a bridge piece 191 secured by screws (Fig. 18) to a block or member 192 which is a movable 130

mate to the fixed block 173 on the upper end of standard 168 heretofore described. There are a series of oppositely positioned sockets preferably of circular cross-section in the 5 adjacent edges of the blocks 173 and 192. Thus there are three relatively shallow sockets 193 in the edge of block 173 which sockets are intersected by the three thread-eyes or passages 174, respectively. Three 10 deeper sockets 194 are correspondingly positioned in the opposing edge of block 192. When the threads are not being gripped, that is when the two blocks are in separated or what may be termed "open" position, as 15 illustrated in full lines in Fig. 18, three cylindrical plungers 195 span the space between the edges of the blocks, each plunger projecting at its opposite ends into one of the sockets 193, and a corresponding socket 20 194, having been moved to and being retained in such position by a coiled expansion spring located in socket 194 about a stem 196 on the plunger, said stem having a screw-threaded end projecting through the 25 end of the socket and carrying a round milled edge nut threaded thereon. In the edge of block 192 there are also two relatively shallow sockets 197, 197, with deeper sockets 198, 198 correspondingly positioned 30 in the edge of block 173. In the position of parts as shown in Fig. 18, two bars 199, 199 secured in the sockets 197, 197 respectively by set-screws, span the space between the edges of the bars and project into the 35 sockets 198, 198, respectively. A stem 200 on each bar 199 extends through the corresponding socket 198 and through an opening in the standard 168 at the end of said socket, the projecting screw-threaded end of 40 said stem carrying a milled edge circular nut 201. A coiled expansion spring 202 in each socket 198 and around each stem 200, bears at one end against corresponding bar 199 and at its other end against the end 45 wall of its socket. In the movement of the lever 183 from its dotted line position to its full line position shown in Fig. 18, the two 50 springs 202 expand and move the block 192 to follow the movement of the lever 183, and thus hold the roller 190 in close contact with the lever during such movement and until the block 192 reaches the limit of its movement determined by contact of the nuts 201, on the stems 200 with the outer surface of 55 standard 168.

The cam 188 is so shaped and timed in its action that during one-half of its rotation—and while the needles are making a descending movement and slack thread to supply such needle movement is being drawn through the thread-eyes 174—the two blocks 173 and 192 remain separated or open substantially as shown in Fig. 18, with the plungers 195 lifted from the bottoms of 60 their sockets 193 and out of alinement with

the thread-eyes or passages 174 through the block 173. During the next succeeding quarter-rotation of the cam 188 it actuates the lever 183 to move it from its full line position to its dotted line position in Fig. 18, 70 and thus moves the block 192 to its closed position relative to the block 173, the plungers 195 passing further into the sockets 193 across the thread-eyes 174 and yieldingly pressing and gripping each thread 75 against the bottom of its socket 193 as best shown in Fig. 17. The parts are maintained in this closed or gripping position practically throughout the last quarter-rotation of the cam 188, and during this period the 80 cam 187 actuates the arm 175 to swing its upper end from a position in approximate alinement with the thread-eyes 172 and 174, to the position in which said lever is shown in Fig. 16, thereby—while the threads are 85 gripped by the plungers 195 as shown in Fig. 17—pulling thread from the source of supply thereof in the receptacles 180 through the thread-eyes 172. The cam 187 then swings the lever 175 in the reverse direction slackening the thread thus drawn 90 from the source of supply through thread-eyes 172 so that the same may be freely drawn forward by the needles in the downward movement thereof without material 95 tension or back pull upon the thread which might tend to pull out the loops thereof just previously projected through the fabric by the needles. Any desired adjustment may be effected by turning the nuts on the ends 100 of rods 200 and 196. With such automatic thread supplying mechanism I can use thread or yarn in the condition of winding in which it is obtainable on the market in its original package, ball, or spool, no re-winding before use being required. 105

It is to be understood that the invention is susceptible of other structural embodiments and that I do not limit myself to the particular embodiment and details of structure herein illustrated and described.

What I claim as new is:—

1. In a sewing or embroidering machine, the combination of a work support, a needle-bar and feed-bar above the work support, a tubular needle carried by said needle-bar and through the interior of which thread or the like is to be conducted and loops thereof projected by the needle through work on the work support, means imparting to the 120 needle-bar and feed-bar endwise reciprocation toward and from the work and sidewise backward and forward movement, and a feed-member pivotally supported from said feed-bar for engagement with the upper 125 surface of the work on the work support.

2. In a sewing or embroidering machine, the combination of a work support, a needle-bar and feed-bar above the work support, a tubular needle carried by said needle-bar 130

and through the interior of which thread or the like is to be conducted and loops thereof projected by the needle through work on the work support, means imparting to 5 the needle-bar and feed-bar endwise reciprocation toward and from the work and sidewise backward and forward movement, and one or more work-engaging feed-members each 10 yieldingly supported from the feed-bar to yieldingly engage and feed the work on the work support.

3. In a sewing or embroidering machine, the combination of a work support, a needle-bar and feed-bar above the work support, a 15 tubular needle carried by said needle-bar and through the interior of which thread or the like is to be conducted and loops thereof projected by the needle through work on the work support, means imparting to the 20 needle-bar and feed-bar endwise reciprocation toward and from the work and sidewise backward and forward movement, and two work-engaging feed-members each 25 yieldingly supported from the feed-bar to yieldingly engage work of the same thickness or of different thickness from that simultaneously engaged by the other member.

4. In a sewing or embroidering machine, the combination of a work support, a needle-bar and feed-bar above the work support, a 30 tubular needle carried by said needle-bar and through the interior of which thread or the like is to be conducted and loops thereof projected by the needle through work on 35 the work support, means imparting to the needle-bar and feed-bar endwise reciprocation toward and from the work and sidewise backward and forward movement, and one or more work-engaging feed-members 40 each yieldingly and pivotally supported from the feed-bar to yield and also rock on its pivot in engaging the work on the work support.

5. In a sewing or embroidering machine, 45 the combination of a work support, a tubular needle through the interior of which thread or the like is to be conducted and loops thereof projected by the needle through the work on the work support, means carrying and reciprocating said 50 needle point downward to cause the same to engage and disengage the work, means for imparting sidewise backward and forward movement to said needle, two feed-members positioned to engage the upper surface of 55 the work at opposite sides respectively of a medial line, means for imparting feed and return movement to said feed-members, and a presser foot positioned to engage the work 60 in the space between said feed-members.

6. In a sewing or embroidering machine, the combination of a work support, a tubular needle through the interior of which thread or the like is to be conducted and loops thereof projected by the needle

through the work on the work support, means carrying and reciprocating said needle point downward to cause the same to penetrate and withdraw from the work, means for imparting sidewise backward and forward movement to said needle, two feed-members each having two arms positioned at opposite ends thereof respectively and each arm projecting toward its corresponding arm of the other member and approximately enclosing a space between the members and their arms, means for imparting feed and return movement to said feed-members, and a presser-foot positioned to engage the work in said space between the feed-members.

7. In a sewing or embroidering machine, the combination of a work support, a tubular needle through the interior of which thread or the like is to be conducted and loops thereof projected by the needle through the work on the work support, means carrying and reciprocating said needle point downward to cause the same to penetrate and withdraw from the work, means for imparting sidewise backward and forward movement to said needle, a feed-member for engaging the upper surface of the work, a feed-bar, means for imparting endwise reciprocation and sidewise backward and forward movement to said feed-bar, and means connecting said feed-member to said feed-bar said means including a yielding element through which the feed-bar applies pressure to press the feed-member into engagement with the work.

8. In a sewing or embroidering machine, the combination of a work support, a tubular needle through the interior of which thread or the like is to be conducted and loops thereof projected by the needle through the work on the work support, means carrying and reciprocating said needle point downward to cause the same to penetrate and withdraw from the work, means for imparting sidewise backward and forward movement to said needle, two feed-members for engaging the upper surface of the work, a feed-bar, means for imparting endwise reciprocation and sidewise backward and forward movement to said feed-bar, and means connecting said feed-members to said feed-bar said means including a separate yielding element for each feed-member through which the feed-bar applies pressure to press said member into engagement with the work.

9. In a sewing or embroidering machine, the combination of a work support, a tubular needle through the interior of which thread or the like is to be conducted and loops thereof projected by the needle through the work on the work support, means carrying and reciprocating said needle point downward to cause the same to penetrate and withdraw from the work,

2

- the combination of a tubular needle through the interior of which thread or the like is to be conducted and loops thereof projected by the needle through the work, means for reciprocating said needle point downward said means being adjustable to change the amplitude of reciprocation of the needle and length of loop projected thereby through the work, a work support, a depending support member thereon, a fixed upright tubular slideway in which said member is slidable up and down, and adjusting means operable to move said member in its slideway and thereby change the elevation of the work support.
18. In a sewing or embroidering machine, the combination of a tubular needle through the interior of which thread or the like is to be conducted and loops thereof projected by the needle through the work, means for reciprocating said needle point downward said means being adjustable to change the amplitude of reciprocation of the needle and length of loop projected thereby through the work, a work support having a depending member fixed thereto, an upright tubular slideway in which said member is slidable up and down, top and bottom supporting plates to which said slideway is fixed, a rack on said depending member, a gear meshing with said rack, and means operable to rotate said gear to slide said member in its slideway and thereby change the elevation of the work support.
19. In a sewing or embroidering machine, the combination with stitch-forming mechanism to which thread is led from a source of supply said mechanism including a tubular needle through the interior of which the thread is to be conducted and loops thereof projected by the needle through work and means actuating said needle, thread-gripping means including two relatively movable members one of which has a socket through which the thread to be gripped passes, a plunger mounted in a socket of the other member, a coiled spring against which said plunger is seated in its socket, and means automatically moving said members towards each other to cause said plunger of one member to yieldingly grip the thread in the socket of the other member and then apart to release said grip upon the thread, and automatically operating thread - pulling means acting upon the thread between its source of supply and the thread-gripping means to pull thread from said source of supply when the thread is gripped by the gripping means and to render said thread available to the stitch-forming mechanism when the thread is released by the thread-gripping means.
20. In a sewing or embroidering machine, the combination with stitch-forming mechanism to which thread is led from a source of supply said mechanism including a tubular needle through the interior of which the thread is to be conducted and loops thereof projected by the needle through work and means actuating said needle, thread-gripping means including two relatively movable members one of which has a socket through which the thread to be gripped passes, a plunger mounted in a socket of the other member, a coiled spring against which said plunger is seated in its socket, and means automatically moving said members towards each other to cause said plunger of one member to yieldingly grip the thread in the socket of the other member and then apart to release said grip upon the thread, and automatically operating thread - pulling means acting upon the thread between its source of supply and the thread-gripping means to pull thread from said source of supply when the thread is gripped by the gripping means and to render said thread available to the stitch-forming mechanism when the thread is released by the thread-gripping means.

and its member, and means automatically and alternately moving said members first together to cause said plunger of one member to yieldingly grip the thread in the socket of the other member and then apart to release said grip upon the thread, and automatically operating thread - pulling means acting upon the thread between its source of supply and the thread-gripping means to pull thread from said source of supply when the thread is gripped by the gripping means and to render said thread available to the stitch-forming mechanism when the thread is released by the thread-gripping means.

20. In a sewing or embroidering machine, the combination with stitch-forming mechanism to which thread is led from a source of supply said mechanism including a tubular needle through the interior of which the thread is to be conducted and loops thereof projected by the needle through work and means actuating said needle, thread-gripping means including two relatively movable members one of which has a socket through which the thread to be gripped passes, a plunger mounted in a socket of the other member, a coiled spring against which said plunger is seated in its socket, and means automatically moving said members towards each other to cause said plunger of one member to yieldingly grip the thread in the socket of the other member and then apart to release said grip upon the thread, and automatically operating thread - pulling means acting upon the thread between its source of supply and the thread-gripping means to pull thread from said source of supply when the thread is gripped by the gripping means and to render said thread available to the stitch-forming mechanism when the thread is released by the thread-gripping means.

In testimony whereof I have signed this specification.

WILLIAM H. BARNETT.
